UNITED STATES PATENT OFFICE

HARRY A. DWYER, OF MARION, INDIANA

DESIGN FOR A PLATE OR SIMILAR ARTICLE

Application filed January 11, 1930. Serial No. 34,105. Term of patent 7 years.

To all whom it may concern:

Be it known that I, HARRY A. DWYER, a citizen of the United States, residing at Marion, Indiana, in the county of Grant and State of Indiana, have invented a new, original, and ornamental Design for a Plate or Similar Article, of which the following is a specification, reference being had to the accompanying drawings, forming part hereof.

I claim:

The ornamental design for a plate or similar article substantially as shown and described.

HARRY A. DWYER.
